UNITED STATES PATENT OFFICE.

CHARLES M. BRONSON, OF LABELLE, MISSOURI.

STEAM-BOILER.

SPECIFICATION forming part of Letters Patent No. 773,049, dated October 25, 1904.

Application filed March 12, 1904. Serial No. 197,800. (No model.)

To all whom it may concern:

Be it known that I, CHARLES M. BRONSON, a citizen of the United States, residing at Labelle, in the county of Lewis and State of Missouri, have invented certain new and useful Improvements in Steam-Boilers, of which the following is a specification.

This invention relates to steam-boilers, particularly those employed with traction-engines, in which the steam used is intended to be dry and is taken for the engine from the high end of the boiler, whether going up or down hill.

The invention consists in automatic means for controlling the passage of the steam from either one of the steam-domes and in a bypass pipe to insure the escape of the steam when the level of the water in the boiler is too high.

The invention is shown in the accompanying drawings, in which—

Figure 1 is a longitudinal vertical section of a steam-boiler constructed in accordance with my invention. Fig. 2 is a transverse vertical section of the same.

In said drawings, A represents the body of the boiler, and B B² the steam-domes thereof, one of which is located on top of the boiler, near one end thereof, and the other near the opposite end. Said two domes are connected together by steam-exit pipes C, which lead into a pipe D, and the latter is intended to lead the steam to the engine. The opening in the top of each steam-dome is provided internally with a conical valve-seat *b*, adapted to receive a corresponding conical valve *e*, which is mounted on the upper end of a valve-rod E, the lower end of which is attached to and carried by a hollow float F. The valve-rod E is guided and maintained in a vertical position by metal straps *f*, screwed to the inside of each steam-dome, through which straps the valve-rod passes freely. When one end of the boiler is elevated while the traction-engine is ascending a hill, the float F at that end descends with the level of the water and also its valve *e*, leaving the steam-opening of the steam-dome at that end fully open for the passage of dry steam; but at the same time the level of the water becomes higher in the opposite end of the boiler, and the float becomes higher and its valve *e* closes

the opening in the top of the steam-dome at that end and prevents the passage of wet steam or water to the engine.

The boiler is provided with a steam-gage *g*, of usual construction, mounted in a convenient location on one of the steam-domes, and said gage may be placed on each steam-dome. It is also provided with a safety-valve *H* and an alarm or steam whistle *h*.

To insure the safety of the boiler in case the level of the water is much above the normal level or in case the valves happen to stick in their seats and either the steam-gage or the safety-valve and whistle indicate "danger," one of the steam-domes is provided on one side with a by-pass pipe K, which is adapted to lead steam from said steam-dome into the pipe C. Said pipe K is provided with a valve L, which can be opened with a hand-wheel *l*. Said valve is generally kept closed; but it may be kept slightly open, as its level can be higher than the steam-dome. Both steam-domes may have by-pass pipes, each one provided with a hand-valve.

Having now fully described my invention, I claim—

1. The combination of the body of a steam-boiler, a steam-dome near each end, and pipes connecting the top of each dome to the other, a valve-seat in each dome, leading to said pipes, a valve and its rod vertically guided in each dome and a float carrying each valve-rod and automatically operated by the water and its changeable level within the boiler, substantially as described.

2. The combination of the body of a steam-boiler, a steam-dome on each one of its ends and exit-pipes connecting the top of each dome to the other, a valve-seat in each dome having an opening leading to each pipe, a valve and its rod vertically guided in each dome and a float carrying each valve-rod, a by-pass pipe additionally leading from one of the steam-domes to the steam-exit pipes, and a hand-valve on said by-pass pipe, substantially as described.

In testimony whereof I affix my signature in presence of two witnesses.

CHARLES M. BRONSON.
